TABLE

Edwin W. North, Rockford, Ill., assignor, by
mesne assignments, to Landstrom Furniture
Corporation, Rockford, Ill., a corporation of
Illinois

Application June 30, 1930, Serial No. 464,761

31 Claims. (Cl. 311—55)

- This invention relates to tables of the refectory type in which the area of the table top may be enlarged by one or more leaves which are normally stored in inoperative position beneath the top. 5 table top and are so connected with the top that they may be disposed in operative position flush with the top and forming extensions thereof by simply pulling the leaves horizontally out from beneath the top.
- 10 One of the primary purposes of this invention is to provide mountings for the slidable leaves which will permit the leaves to be moved from inoperative to operative positions and vice versa with the exertion of but slight effort by simply 15 grasping the leaves and exerting a slight pull or push thereon and without the necessity of reaching under the table to manipulate any locking or fastening means.

Another purpose of the invention is to provide 20 controlling means for the table leaves which will automatically bring the leaves into a position flush with the table top when the leaves are pulled out and which will automatically lower the leaves as they are slid beneath the table top.

A further feature of my invention resides in the 25 provision of means which automatically locks the leaves in their operative position against accidental displacement and automatically retains 30 the leaves flush with and snugly against the table top so that the leaves form extensions of the top itself disposed in the same plane as the top and abutting the ends thereof, leaving no appreciable 35 crack or opening between the top and its extensions.

Another object of the invention is to insure 40 easy, smooth and accurate operation of the leaves by providing for adjustment of the leaf controlling mechanism so that compensation may be made 45 when necessary for variation in the thickness of the table parts and for distortion of these parts which sometimes occurs through warping of the wood or from other causes.

A preferred embodiment of the invention is de- 50 scribed in the following specification and illustrated in the accompanying drawings, referring to which:

- Fig. 1 is a side elevation of a table constructed 55 in accordance with this invention;
- Fig. 2 is a horizontal sectional view on the line 2—2 of Fig. 1, looking upwardly beneath the table;
- Fig. 3 is a vertical section on the line 3—3 of Fig. 2;
- Fig. 4 is a vertical sectional view taken from the

same position as Fig. 3 but with the two table leaves extended to operative position;

Fig. 5 is a vertical sectional view on the line 5—5 of Fig. 1;

Fig. 6 is an enlarged perspective of a locking mechanism; 5

Fig. 7 is an enlarged perspective of a center bracket hereinafter described, and

Fig. 8 is a side elevation of the locking mechanism shown in Fig. 6. 10

Referring now to the drawings, there is shown a table having a top 1, legs 2 and certain usual horizontal braces 3, 4, and 5 for imparting rigidity to the construction.

The top 1 is fastened to strips 5' which are 15 in turn secured to the horizontal frame member 4, thus spacing the top upwardly from the frame members 4.

The normal length of the table top shown in 20 Fig. 3 may be increased to the length shown in Fig. 4 by moving the leaves 6 and 7 from their inoperative position beneath the table top illustrated in Fig. 3 to the operative position at the ends of the top and flush therewith, as illustrated in Fig. 4. The leaf 6 is fixedly connected 25 and supported by the outer ends of wooden bars 8 and 9, the inner ends of which extend beneath the table top. The outer face of each bar is provided with a longitudinally extending groove, which is designated 8' in the bar 8 and which terminates at the inner end of the bar in an offset portion 8'', as best shown in Fig. 3. A bracket 11 secured to and depending from the under side of the table top near the middle carries a laterally projecting pin or stud 12 which projects into the 30 aforesaid groove in the bar. When the leaf is in its inoperative position beneath the top, as shown in Fig. 3, this pin 12 is disposed in the upper level 8' of the groove and when the leaf is extended 35 into operative position, as illustrated in Fig. 4, 40 the pin is disposed in the lower level 8'' of the groove so as to raise the bar to a higher level.

The bar 9 is similarly provided with a groove 9' of identical shape with the groove 8' in the bar 8 adapted to receive a similar pin 13 carried by 45 a similar depending bracket 14. The level of both bars 8 and 9 and consequently the leaf 6 carried thereby is raised and lowered by the cooperative action of the offset grooves therein and the pins 50 extending into said grooves.

To extend the leaf 6 to operative position the user simply grasps the leaf 6 and draws it outwardly, causing the grooves 8' and 9' to slide along the stationary pins 12 and 13 as the bars 55 8 and 9 move outwardly, and as the lower portion

8" of the groove 8' in the bar 8 and a corresponding lower groove portion (not shown) in the bar 9 are engaged by their respective pins 12 and 13 the inner end of each bar will thereby be raised. At this time, a pin 15, secured by a bracket 15' to the side of the bar 8, will enter the slot 16 in a locking bracket 17 carried by the brace bar 5 and will ride up the lower cam surface of said slot until the operator, while lifting the leaf 10 when its innermost edge 18 is free of the outer margin of the table top, causes this pin to move upwardly and back into the inner end 21 of the slot. The pin may then rest in the curved inner end 21 of the slot and thus hold the top of the 15 table leaf flush with the surface of the table top. As the pin 15 moves into the slot 16, it will strike a locking bar 22, push the same backwardly about the pivot 22' against the tension of the spring 23 until the pin moves into the recess 21 whereupon the locking bar follows the pin and releasably locks it in an obvious manner. The construction of the locking bracket 17 is amply shown in Fig. 6, and its coaction with the pin 15 will be readily understood by reference to that figure. 25 A stop 24 is provided in the form of a shoulder struck up from the bracket to limit the rotation of the bar 22 under the action of the spring. The bar or extension 9 is provided with a pin 25 (see Fig. 2) mounted on a bracket 25' which corresponds in location and function to the pin 15 carried by the bar 8. To cooperate with the pin 25 and the bar 9 another bracket 17, similar to the one shown in Fig. 6, is mounted in the position shown in Fig. 2 and functions as above described.

To return the leaf 6 to its concealed and inoperative position, the operator merely grasps the leaf, pulls it outwardly so that the pins 15 and 25 push the locking bars 22 of the brackets 17 back, 40 and this enables the operator to slide the pins downwardly and out of the slots 16, whereafter the operator can then push the table leaf underneath the table top.

The contour of the grooves 8' and 9' is such 45 that in either extreme position of the table leaf the bars connected thereto will be held horizontally so that the surface of the table leaf will also maintain a horizontal position.

It will be observed that the table leaf 7 is provided with bars or extensions 26 and 27 constructed exactly like the bars 8 and 9 and provided respectively with similar grooves 26' and 27'. The grooves in the bars 26 and 27 coact respectively with pins 28 and 29, which are in turn carried respectively by brackets 31 and 32 affixed to the under side of the table top. Likewise, a locking pin 33 is carried by the bar 26, and another similar pin 34 is carried by the bar 27 for locking the leaf 7 in extended operative position in cooperation with locking brackets 17 similar to the bracket 17 shown in Fig. 6.

In the embodiment herein shown, inasmuch as the pin 33 (see Fig. 2) protrudes far enough outwardly from the side of the bar 26 to engage the locking bracket 17, it necessarily also would interfere with the inner end of the bar or extension 8, were it not for the fact that an elongated recess 33', shown in Fig. 2, is cut into the side of the bar 8 to allow these two bars, one carrying the protruding pin 33, to pass freely by each other. A correspondingly similar groove 34' is cut into the face of the bar 9 to prevent interference by the pin 34.

In operation, both leaves and their associated mechanism function exactly alike. One who de-

sires to extend the leaf 6 from the position shown in Figs 1 or 3 into the position shown in Fig. 4 will grasp that leaf, pull it horizontally outwardly while the upper level of the grooves 8' and 9' slide past the stationary pins 12 and 13, and as the leaf approaches its fully extended position, the lower portions of the grooves 8' and 9' ride up on the pins 12 and 13 respectively, lifting the inner ends of the bars while the operator manually lifts the leaf itself as he forces the pins 15 and 25 through the slots 16 into the locking recesses 21 of the brackets 17, momentarily forcing the locking bars 22 rearwardly but allowing them eventually to come forward and hold the pins 15 and 25 in locked position in the recesses 21. Since the inner end of the bar 8 and, likewise the inner end of the bar 9, both rest horizontally and substantially up against the under side of the table top, the leaf 6 will be maintained in horizontal position with its surface flush with the table surface.

The various parts of the mechanism will preferably be so proportioned as to position the adjacent edges of each leaf and the table top close to each other to minimize the aperture therebetween. Abutting contact between the opposed edges of the table top and leaf is assured by the pull of the springs exerted through their respective locking bars upon the pins projecting from the leaf supporting bars.

To release either leaf, the operator will merely slightly lift it and pull it outwardly to disengage the pins from their respective locking recesses in the brackets 17, drop the leaf and push it underneath the table top.

The supporting bars for the leaves and their associated locking brackets 17 are widely spaced from the longitudinal center line of the table and thus afford a firm support for the extended leaves thereby precluding tilting.

It will be noted that when the leaves 6 and 7 are not in use, they are aligned with the table top and present a neat appearance. If desired, horizontal strips 36 and 37 (see Fig. 5) may be attached to the under side of the table top so that when the table is in shortened position the entire side edge of the table from end to end will have the same thickness and hence a uniform appearance. (See Fig. 1.)

It will be further noted that when the leaves are in their inoperative positions, they are virtually concealed or at least scarcely noticeable, and furthermore neither do they or the operating mechanism extend downwardly from the table so far as to make it inconvenient for persons to sit up close to the table.

As it may be desired to employ the same middle locking bracket 17 or the same center brackets such as 11, 13, 31 or 32 on similar tables having tops and leaves of different thicknesses, these locking brackets and center brackets are provided with adjustments. These adjustments also are found useful in case a table leaf or the elongated bars which support it should warp. Referring to the locking bracket shown in Fig. 6, it will be noted that the bracket consists of a main angular body indicated by reference character 17 upon which is disposed a plate 41 provided with three screw holes 42, each of which registers with one of the elongated slots 43 in the body of the bracket. The bracket is secured to either of the braces 5 on the table by means of screws which extend through these holes and cooperating slots, it being obvious that whereas the plate 41 must remain stationary with respect to the table, the bracket 17 may be moved upwardly or downwardly within the range of the lengths of the slots 43.

A lug 44 is struck up from the surface from the plate 41 leaving an aperture 45 through which extends another lug 46 struck up from the bracket 17. The latter lug is provided with a slot 47 whose margins are crimped slightly inwardly to provide a bearing for a screw 48, provided above and below the lug with a shoulder 49 and screw head 51 respectively, the latter being provided with the usual kerf. The head and shoulder permit rotation of the screw but preclude longitudinal movement with respect to the lug 46. By rotating the screw which is threadedly engaged with the lug 44 the bracket 17 will be moved upwardly or downwardly depending upon the direction of rotation, while plate 41 is retained in fixed position by the three screws which pass through the screw holes 42 into the braces 5 of the table. Manipulation of the screw 48 will therefore raise or lower the bracket 17 so that the end 21 of its slot may be adjusted upwardly or downwardly to bring the top of any leaf perfectly flush with the top of the table when the leaf is at its extended position.

The pins 12, 13, 28 and 29 are also capable of adjustment into exact alignment with their grooves in their respective supporting bars so that these bars may slide freely and without binding when employed in connection with leaves of different thicknesses. With this end in view each of these pins is adjustably mounted on its depending supporting bracket. Since all of the brackets and pins are alike, the bracket 11, shown in Fig. 7, may be considered as illustrative. Referring to this figure it will be observed that the bracket may be secured in fixed position to the under side of the table top by means of screws passing through the holes 52. The pin 12 carried by the bracket is formed to provide an annular shoulder 63 and a reduced threaded portion 62 projecting from said shoulder through an arcuate slot 53 in the bracket 11 and also through an opening in the adjusting plate 58. The plate 58 is provided at one end with a tongue 59 adapted to be disposed in an opening 54 in the bracket 11 and about which the plate pivots and at its other end with a similar tongue 61 adapted to be positioned in any one of the three spaced openings 55, 56 or 57 formed in the bracket 11. It will be manifest that the position of the pin 12 with respect to the bracket may be raised or lowered depending upon in which of the three openings the tongue 61 is seated. When the proper adjustment has been made which will align the pin with its groove in the supporting bar so as to insure free sliding movement of the bar, the parts are locked in adjusted position by a nut 64 threaded on to the reduced portion 62 of the pin so as to clamp the bracket 11 and the plate 58 together between the shoulder 63 and the nut 64.

When the bracket is employed with a leaf of medium thickness, the plate 58 will normally be secured in the position shown in Fig. 7. If the center bracket is employed with a leaf of less than medium thickness, the tongue 61 may be inserted into the hole 55 thus slightly elevating the pin 12 and thus by its cooperation with the groove 8' in the bar 8 hold the bar a little bit higher. In such a case, the locking bracket 17 would likewise be adjusted upwardly so that this thinner leaf would be held horizontally and with its surface exactly flush with the table top when extended.

The manner in which a leaf may actually warp will determine just how the adjustable features of the center brackets or locking brackets may

be employed to correct for the warping. When once the warped condition was observed, it would be obvious as to which of the brackets associated with that leaf should be adjusted upwardly or downwardly to cope with the condition.

The constructions herein shown are capable of economical manufacture, are sturdy, so simple as to present little likelihood of maintenance troubles, and may readily be incorporated into a table.

It should be understood that the embodiment herein described has been selected for the purpose of illustrating a preferred form of the invention and that other embodiments may be devised within the spirit and scope of this invention as defined in the appended claims.

Having shown and described this invention, I claim:

1. In combination with a table having a top, and a leaf, means connected thereto for slidably guiding and positioning the leaf horizontally beneath the table top when not in use and for guiding said leaf into operative position beside an edge of and with its top flush with the top of the table including a slotted member for guiding the final outward and upward movement of the leaf, and a spring actuated element coacting with said member for locking the leaf top coplanar with the table top and snugly adjacent thereto.

2. A refectory table comprising a top, a horizontally slidable leaf, a supporting bar therefor having a pin projecting laterally therefrom, means for elevating said bar upon outward movement thereof whereby to dispose said leaf flush with the table top, a metal fixture arranged to be detachably engaged by the pin to support said bar and leaf in elevated position, and spring actuated means arranged to be placed under load in the inter-engagement of the pin and fixture so as to releasably lock the bar and hold the leaf under constraint to move inwardly toward close engagement with the top.

3. A refectory table comprising a top, an extensible leaf, a support for the leaf, means for elevating the leaf when the support is extended and lowering the leaf when the support is retracted, and means whereby said elevating and lowering means may be adjusted relatively to the table top.

4. A refectory table comprising a top, an extensible leaf, and means rendered operable by horizontal movement of the leaf to impart a vertical movement to the leaf, said means including brackets fixed with respect to the table top and having operative portions adjustable relatively to the table top.

5. A refectory table comprising a top, an extensible leaf, supporting means thereof, and means cooperating with said supporting means to impart vertical movement to the leaf as the leaf is moved horizontally, said last mentioned means including adjustable devices whereby said vertical movement may be regulated.

6. A refectory table comprising a top, an extensible leaf, horizontally slidable supporting means therefor, and means including brackets having portions fixed to said top and portions adjustable relatively to the top for imparting vertical movements to said leaf upon horizontal movements of said supporting means.

7. A refectory table comprising a top, an extensible leaf, a horizontally slidable support for said leaf, and means rendered operable by horizontal movement of the leaf for imparting vertical movement thereto, said means including a

- bracket fixed with respect to the table top and a member adjustably mounted on said bracket in position to cooperate with said supporting means.
8. A refectory table comprising a top, an extensible leaf, a horizontally slidable support for said leaf, and means rendered operable by horizontal movement of the leaf for imparting vertical movement thereto, said means including a bracket fixed to the table top and a pin adjustably mounted on said bracket and adapted to cooperate with said supporting means.
9. A refectory table comprising a top, an extensible leaf, a horizontally slidable support for said leaf, and means rendered operable by horizontal movement of the leaf for imparting vertical movement thereto, said means including a bracket depending from the table top, a plate adjustably mounted on the bracket and a pin carried by said plate.
10. A refectory table comprising a top, an extensible leaf, a horizontally slidable support for said leaf, and means rendered operable by horizontal movement of the leaf for imparting vertical movement thereto, said means including a fixed bracket provided with a slot and a plurality of apertures, a plate adapted to engage in a selected one of said apertures, a pin carried by said plate and means for clamping said plate in adjusted position to said bracket.
11. A refectory table comprising a top, an extensible leaf, supporting means for said leaf, a pin carried by said supporting means, and a bracket adapted to cooperate with said pin to hold the leaf in elevated position and yieldingly lock the same against displacement, said bracket comprising a portion fixed to the table, a portion adjustably mounted on the fixed portion and a spring actuated latch bar.
12. A refectory table comprising a top, an extensible leaf, slidable supporting means for said leaf, and a bracket cooperating with said supporting means to hold the leaf in elevated position and yieldingly lock the same against displacement, said bracket comprising a member fixed to the table, a second member adjustably mounted on the first member and provided with a curved slot, a pivotally mounted latch bar extending across said slot and a spring acting upon said latch bar.
13. A refectory table comprising a top, an extensible leaf, slidable supporting means for said leaf provided with a laterally extending pin, and a bracket cooperating with said pin to hold the leaf in elevated position and to yieldingly lock the same against displacement, said bracket comprising a member fastened to the table, provided with a curved slot for receiving said pin, a pivotally mounted latch bar extending across said slot, and a spring acting upon said latch bar for yieldably holding said pin in said slot against movement from the extremity of said slot, the end portion of said slot being shaped to hold the pin snugly against vertical movement.
14. In a draw table, the combination of a frame, a table top supported thereon, a draw leaf, slides reciprocable on the frame and serving to support the draw leaf in a position substantially coplanar with the table top, a fixed means of support on the frame for the inner ends of the slides, an adjustable means of support for the slides on the frame intermediate the ends of the slides, and a screw adjustment for the last mentioned means whereby the draw leaf is arranged to be adjusted into alignment with the table top.
15. In a draw table, the combination of a frame, a table top supported thereon, a draw leaf, slides reciprocable on the frame and serving to support the draw leaf in a position substantially coplanar with the table top, two means of support for the slides on the frame, one of said means serving to support the slides at the inner ends thereof and the other intermediate the ends thereof, the one means of support being fixed and the other vertically adjustable, and means for adjusting the last mentioned means.
16. In a draw table, the combination of a frame comprising a cross-rail, a table top supported on said frame, slides reciprocable in the frame relative to the cross-rail, a draw leaf carried on the slides and arranged to be supported thereby in a position coplanar with the table top, means rigid with the frame cooperating with the inner ends of the slides for supporting and guiding the same for reciprocatory movement, brackets fastened to the cross-rail and serving to support the slides intermediate their ends, the fastenings for said bracket being arranged to be loosened to permit the same to be adjusted and being arranged to be retightened to fasten the same in adjusted position, and means for vertically adjusting said brackets and for rigidly supporting the same in adjusted position comprising secondary brackets fixedly secured to the cross-rail, and jack screws extending between said brackets and arranged when turned to effect vertical adjustment of the first brackets.
17. In a draw table comprising a frame, a table top supported thereon and a draw leaf arranged to be placed in coplanar relation with the top, the combination with a cross-member of the frame and a slide attached to the draw leaf reciprocable in an opening provided in the cross-member, of a pin projecting laterally from the slide for supporting the same on the cross-member, a bracket adjustably mounted on the cross-member for reception of the pin, a secondary bracket rigid with the cross-member, and an adjusting screw extending from the one bracket to the other and arranged when turned to move the first bracket in one direction or the other relative to the secondary bracket for the purpose herein described.
18. In combination with an extension table having a leaf supported by runners slidable in the cross rails of the supporting frame for movement of the leaf from housed to extended position, said runners having a pin projecting laterally therefrom, of a metal fixture attached to the inner side of the end rail for engagement of the pin in guiding the movements of the leaf, said fixture having an inturned supporting member at its upper end with a depressed seat in which the pin rests in positioning and holding the extension leaf on a horizontal plane with the top of the table, and a spring actuated keeper on said fixture for releasably holding the pin on the seat.
19. A metal fixture for extension tables comprising an attaching plate, a member projecting outwardly therefrom, and a curved portion at the outer end of said member forming a support for a member on a table leaf slide, and a spring actuated keeper on said outwardly projecting member for releasably holding the table leaf slide member on said support.
20. A metal fixture for extension tables comprising an attaching plate, an outwardly projecting guiding member at the upper end thereof.

and a downwardly and inwardly projecting portion at the outer end of said member, the inwardly projecting portion having a depression in its upper edge forming a seat, and a spring actuated keeper on said outwardly projecting member tending normally to move toward said seat to retain a part in engagement therewith.

21. A metal fixture for extension tables comprising an attaching plate, a vertical rib projecting from said attaching plate to form a vertical guide, an outwardly projecting member at the upper end of said rib, and a downwardly and inwardly projecting portion at the outer end of said member, the inwardly projecting portion having a depressed seat in its upper edge, and a spring actuated keeper on the vertical rib tending normally to move toward the seat to releasably hold a member in engagement therewith.

22. In combination with an extension table having a leaf supported by runners slidable in a slot in the cross rails of the supporting frame for movement of the leaf from housed to extended position, said runners having a member projecting laterally therefrom, of a metal fixture attached to the end rail at one side of the slot for engagement of the member in supporting the leaf, said fixture consisting of an attaching plate, and a supporting member the upper end of which extends at an angle to the attaching plate and is curved to form a seat for the aforesaid member on the runner supporting the leaf, and a spring actuated keeper on said supporting member for releasably holding the member on the runner in engagement with the seat.

23. In an extension table, the combination of a runner carrying the extension leaf, and a rail on the supporting frame having a slot at the bottom of which the runner slides and by which it is guided in the movement of the leaf to extended and housed positions, together with means for supporting the leaf and its runner in position against horizontal displacement comprising a supporting member attached to one of the aforesaid parts of the table, and a supporting fixture attached to the other of said parts, said fixture having a hook member and an entrance slot leading to the bill of the hook by which the aforesaid member on the companion part of the table passes in the interlocking engagement thereof with the hook, and a spring actuated keeper on the hook member of said fixture for releasably holding the runner engaged on the hook.

24. In an extension table, the combination of a runner carrying the extension leaf, and a rail on the supporting frame having a slot at the bottom of which the runner slides and by which it is guided in the movement of the leaf to extended and housed positions, together with means for supporting the leaf and its runner in position against horizontal displacement comprising a supporting member attached to one of the aforesaid parts of the table, and a supporting fixture attached to the other of said parts, said fixture having a hook member and an entrance slot leading to the bill of the hook by which the aforesaid member on the companion part of the table is guided and interlocked with the fixture against horizontal movement, a keeper bar pivoted at its lower end on the fixture so that its upper end extends across the end of the hook member, and a spring for urging said bar in one direction so as to releasably lock the runner in engagement with the hook.

25. In combination with an extension table having a leaf supported by runners slidable in

the cross rails of the supporting frame for movement of the leaf from housed to extended position, said runners having a pin projecting laterally therefrom of a metal fixture attached to the inner side of the end rail for engagement of the pin in guiding the movements of the leaf, said fixture having an inturned supporting member at its upper end with a depressed seat in which the pin rests in positioning and holding the extension leaf on a horizontal plane with the top 10 of the table, and a screw adjustment for said fixture whereby the extension leaf supported thereon is arranged to be vertically adjusted.

26. A metal fixture for extension tables comprising an attaching plate, a member projecting 15 outwardly therefrom, and a curved portion at the outer end of said member forming a support for a member on a table leaf slide, and a screw adjustment whereby the outwardly projecting member is arranged to be vertically ad- 20 justed.

27. A metal fixture for extension tables comprising an attaching plate, an outwardly projecting guiding member at the upper end thereof, and a downwardly and inwardly projecting portion at the outer end of said member, the inwardly projecting portion having a depression in its upper edge forming a seat, and a screw adjustment whereby the outwardly projecting guiding member is arranged to be vertically adjusted. 30

28. A metal fixture for extension tables comprising an attaching plate, a vertical rib projecting from said attaching plate to form a vertical guide, an outwardly projecting member at the upper end of said rib, and a downwardly and in- 35 wardly projecting portion at the outer end of said member, the inwardly projecting portion having a depressed seat in its upper edge, a second attaching plate, and a screw adjustment for vertically adjusting the first attaching plate with respect 40 thereto.

29. In combination with an extension table having a leaf supported by runners slidable in a slot in the cross rails of the supporting frame for movement of the leaf from housed to extended 45 position, said runners having a member projecting laterally therefrom, of a metal fixture attached to the end rail at one side of the slot for engagement of the member in supporting the leaf, said fixture consisting of an attaching plate, and a 50 supporting member the upper end of which extends at an angle to the attaching plate and is curved to form a seat for the aforesaid member on the runner supporting the leaf, and a screw adjustment for vertically adjusting the supporting 55 member with respect to the attaching plate.

30. In an extension table, the combination of a runner carrying the extension leaf, and a rail on the supporting frame having a slot at the bottom of which the runner slides and by which it is guided in the movement of the leaf to extended 60 and housed positions, together with means for supporting the leaf and its runner in position against horizontal displacement comprising a supporting member attached to one of the aforesaid parts of the table, and a supporting fixture attached to the other of said parts, said fixture having a hook member and an entrance slot leading to the bill of the hook by which the aforesaid member on the companion part of the table passes 65 in the interlocking engagement thereof with the hook, and a screw adjustment whereby the supporting fixture is arranged to be vertically ad- 70 justed.

31. In an extension table, the combination of 75

5 a runner carrying the extension leaf, and a rail on the supporting frame having a slot at the bottom of which the runner slides and by which it is guided in the movement of the leaf to extended and housed positions, together with means for supporting the leaf and its runner in position against horizontal displacement comprising a supporting member attached to one of the aforesaid parts of the table, and a supporting fixture attached to the other of said parts, said fixture hav-

5 ing a hook member and an entrance slot leading to the bill of the hook by which the aforesaid member on the companion part of the table is guided and interlocked with the fixture against horizontal movement, a secondary supporting fixture relative to which the first supporting fixture is vertically adjustable, and an adjusting screw extending vertically between said fixtures for effecting such vertical adjustment.

EDWIN W. NORTH. 10
